MANIFOLDING CONTINUOUS STATIONERY

Marcus S. Roosevelt and George L. Bezold, Hamilton, Ohio, assignors to The Hamilton Autographic Register Company, Hamilton, Ohio, a corporation of Ohio

Application September 16, 1937, Serial No. 164,208

5 Claims. (Cl. 282—12)

This invention relates to improvements in manifolding continuous stationery, consisting of a plurality of package supply continuous length of form printed or form subdivided strips collocated for form registration to provide a composite web with manifolding material interposed or interleaved between the strips to render the composite web ready for use within a writing machine for the purpose of filling in the forms.

10 In the use of continuous form stationery for typewriting and billing machines, in manifolding it has been advantageous to include the transfer medium as a component with the several collocated form strips of a composite web to eliminate the complications and time consuming manipulations by a typist, as experienced in the methods in which the transfer medium is mounted or carried by a fixture of the type of writing machines, requiring repeated shifting for repositioning or adjusting the transfer medium from an advanced to a succeeding set of forms at the completion of a writing operation or interval.

It, therefore, has been the practice to incorporate the transfer medium in strip length corresponding to the supply length of form stationery, and the parts of the composite web appropriately clipped or fastened together at suitable intervals and folded for packaging. In packaging, the composite web is preferably zig-zag or fan folded, the folds usually coinciding with weakened transverse tear lines in the strips for separating the form sets one from another or from the composite web as they are filled in.

The strips are usually provisioned for obtaining a separate fingerhold upon the form and transfer sheets respectively of a set, when severed from the composite web, for accommodation in extracting or withdrawing the carbon sheets from the form sheets. In some instances the weakened line of tear in the transfer medium or carbon-coated strip is slightly offset from the corresponding tear lines of the work or form strips for obtaining the designated fingerhold. The carbon sheets are thus of a corresponding 45 or full length of the work or form sheets and, as the work or form sheets of each set usually contain a printed heading or non-writing margin, an appreciable area of the carbon sheet is not subjected to use, which, when multiplied for 50 the full length of the packaged web, constitutes a surplus adding materially to the cost, particularly when the transfer material bears a higher cost than the form material, and therefore exceedingly wasteful, even when considering that the carbon material is intended only

for a single use and that this permits the use of a low cost grade or quality.

It is therefore an object of the invention to provide manifolding continuous form stationery, consisting of a composite web formed of a plurality of collocated form strips, zig-zag or fan folded for packaging, the strips having transverse weakened tearing lines coincident with the lines of fold, with transfer or carbon-coated sheets interleaved between the registering forms, or 10 spacing between the transverse tearing lines, and of reduced length dimension therefrom proportionate to a space prescribed for writing to effect economy and minimize the amount of transfer material employed. 15

Another object of the invention is to provide manifolding continuous form stationery, composed of a plurality of form strips with interposed or interleaved carbon-coated or transfer sheets, each of the transfer sheets being of reduced size respectively to that of the form for which it serves and secured to the strips to prevent disarrangement and temporarily bind the same, with the strips readily releasable therefrom upon severing a form length set from the composite web, while binding or retaining the carbon sheets of a set together. 20

Another object of the invention is to permanently bind carbon sheets of a form set together and to temporarily bind the same to the form 30 strips between which they are interposed, by a fastener of thin sheet ductile metal or any other satisfactory material, which will not interfere or impede the feed of a composite web over a cylindrical platen of a typewriting machine. 35

Various other objects and features of the invention will be more fully set forth in a description of the accompanying drawing, in which:

Figure 1 is a plan view of a portion of a composite web of form stationery, illustrating a foremost section or set of sheets partially separated from the web along a transverse weakened tear line, and illustrating the components of the web clipped together by a metallic fastener. 40

Figure 2 shows a detached set of forms, in the 45 act of extracting or withdrawing the carbon sheets.

Figure 3 is an enlarged detail view, face-side, of a central edge portion of a set of forms before extracting the carbon sheets. 50

Figure 4 is an enlarged detail view of the lower or under-side of a central edge portion of a set of forms before extracting the carbon sheets. 55

Figure 5 is a view corresponding to Figure 3, 55

showing the carbon sheets partially withdrawn or extracted.

Figure 6 is an enlarged section on line 6—6, Figure 3.

5 Figure 7 is a perspective view of a package of manifolding continuous form stationery, embodying the present improvements, with a section thereof unfolded to expose a form set, one edge or corner of the components being turned up for respectively exposing the sheets.

10 Referring to the drawing, 1, 2 and 3 indicate a plurality of strips of continuous form stationery in relative superposed arrangement for manifolding, and provide a composite web. The strips are printed to provide successive form blanks and their determined length size is governed by the spacing of transverse weakened tearing lines 4, along which a set for forms, as a unit, is separated from the composite web.

15 20 The web is preferably flat packaged by zig-zag or fan folding, the folds being coincident with the registering tearing lines of the several strips. Each of the strips longitudinally and preferably centrally of its width, is apertured at intervals, 25 the apertures being of an outline configuration so that a portion thereof coincides with a tearing line to open the apertures in severing the strip along the tear line. The aperture is within the lower margin of a form length to expose the carbon sheets underlying the same or interleaved between a pair of registering form sections for obtaining a fingerhold upon the carbon sheet or sheets of a form set when detached from the web, for carbon sheet withdrawal or extraction.

30 35 The carbon-coated or transfer sheets 6 are interleaved between the strips, each to serve a pair of registering forms, and are preferably of a length size short of the length of the form, with one end thereof, as a lower edge, coinciding with 40 a tearing line, to omit serving or supplying a margin at the opposite end of the forms, used as a heading space, and also to free the carbon sheets from finger grasp while holding the form sheets of a set in extracting the carbon sheets. 45 The length size of the carbon sheets therefore is only sufficient to supply the prescribed entry or writing space of a form sheet for effecting economy in the amount of carbon sheet material employed.

50 55 The carbon sheets for the composite web are correspondingly arranged in a successive order and the carbon sheets comprised in a form set are clipped together through registering apertures 7 of the several form strips, by a ductile sheet metal or any other satisfactory material fastener 8, which may either be pierced through the carbon sheets or extended through an aperture thereof. The fastener permanently binds the carbon sheets of a form set together and 60 frictionally binds with the form strips to prevent relative displacement of the parts, and temporarily binds the carbon sheets to the form sheets of a set when separated or detached from the composite web.

65 70 75 The various parts are thus securely held in place, with the forms of a set in registry and the carbon sheets interleaved therebetween, are of appropriate length to serve the transcribing or writing space of the form so that no adjustment of the parts is required for loading in a typewriter, nor is their relative arrangement disturbed in their feeding advance by the typewriter. When a form set has been typed or autographed and advanced sufficiently for detachment from the web, the typed form set is easily separated

from the web along the weakened tearing line. The tear-off opens the apertures in the form sheets through which the fastener is clipped to permit the same to be slipped edgewise off of the forms with the carbon sheets in extracting the 5 carbon sheets from between the form or work sheets by pulling the same in opposing directions, by grasping the carbon sheets by the finger of one hand at the fastener and gripping the form sheets at the opposite edge with the other hand, 10 at which end the carbon sheets are free from the form or work sheets.

15 It is much easier to separate the forms at the tear lines of the record strips after a typing operation with a manifolding material, as intervening sheets over the type of stationery in which the manifolding material is in strips have tear lines coincident with the tear lines of the record strips, the resistance against tear increasing with the number of plies employed. In the present instance, a carbon being cut in sheets in a shorter length than the form, permits grasping of the record copies at one end of the sheets without obtaining a hold upon the carbons, while the carbons are grasped at on opposite end, thereby 25 materially facilitating separation of the respective sheets.

30 35 The fastener 8 preferably comprises a very thin ductile sheet metal wafer of oblong outline and dimension to over-spread the aperture 7 in the strips for binding the strips together and to the carbon sheets. The body portion of the fastener preferably bears upon the face-side of the uppermost sheet or strip of the series or set, and is punched to provide a pair of opposingly 40 directed tangs 9, bent at right angles to the body and pierced either through the carbon sheets or traversed through apertures therein. The free ends of the tangs are clinched laterally to bind against the under-side of the lowermost 45 sheet or strip of the series, as illustrated in Figure 6.

50 55 With the fasteners traversing apertures in the strips, binding the strips and carbon sheets interleaved therebetween against disarrangement, 45 upon severing or detaching a set of forms from the web along a tear line, the apertures 7 are opened, thereby permitting the fastener to be slipped edgewise from the form sheet, retaining and permanently binding the carbon sheets, 50 which facilitates in the extraction of the carbon sheets from the form or work sheets. The fastener also temporarily binds all the parts of a set together, until the carbon sheets are partially extracted to free the fastener from its bind or 55 grip upon the form sheets.

60 The fastener, being of a very thin gauge ductile sheet material, bends or flexes with the paper as the web is loaded or advanced in the typewriter, so that it presents no impedance or interference to the feeding advance of the web.

Having described our invention, we claim:

1. A manifolding packet of the class described, comprising a composite web composed of a plurality of collocated strips zig-zag folded, the strips 65 having transverse weakened tearing lines coincident with the lines of fold dividing the web into laminated sections, a sheet of transfer material interposed between each pair of laminations of a section with an edge thereof bordering a transverse weakened tearing line, and a metallic fastener clipping the laminations and the transfer sheet or sheets of a section together adjacent a tear line, a portion of the fastener passing through an aperture in the web section, the aper- 70 75

tures opened upon tearing the web section from the web along the tear line to release the fastener from the laminations and permit extraction of the transfer sheet or sheets therefrom.

5 2. A composite record strip assembly comprising a plurality of record strips zig-zag folded, each having longitudinally spaced transverse weakened severance lines respectively coincident with the lines of fold to divide the same into sheet 10 groups for simultaneous severance, a transfer sheet having a coating of transfer material, interposed between the superposed sheets of each group and a fastener engaged through the transfer sheets and through registering apertures in the 15 record sheets of each group and embracing the record sheets beyond the area of the apertures for binding all of the elements of a group together, the apertures of the sheets of a group opened upon severance along a severance line to release the fastener from the record strips while continuing its binding of the transfer sheets.

20 3. A composite record strip, comprising: a plurality of record strips zig-zag folded, each having longitudinally spaced transverse weakened severance lines respectively coincident with the lines of fold to divide the same into record sheet groups for simultaneous severance, a transfer sheet interposed between the superposed sheets of each group, and having an edge substantially coinciding with the line of fold and a fastener for binding all of the elements of a group together, having a portion thereof engaged through the transfer sheets and through registering apertures in the record sheets of each group, the apertures of the record sheets of a group opened upon severance along a severance line to release the fastener 25

from the record sheets while continuing its binding of the transfer sheets.

4. A manifolding packet of the class described, comprising a plurality of sheets of manifolding paper in superposed relationship, sheets of transfer material interposed between the adjacent sheets of manifolding paper, said sheets of manifolding including registering notches in their end edges, a fastener for binding said sheets of manifolding paper and said transfer sheets together, 10 said fastener engaged through the transfer sheets and through the notches and engaging the manifolding sheets beyond the area of the notches, whereby the fastener carrying the transfer sheets may be withdrawn from the notches for removing 15 the transfer sheets as a unit from between the manifolding sheets.

5. A manifolding packet of the class described comprising a plurality of sheets of record paper in packet form, sheets of transfer material interposed between said sheets of record paper, said sheets of transfer paper stopping short of the one end edge of said sheets of record paper, fastening means for binding said sheets of transfer paper together, said fastening means traversing 20 the sheets of transfer paper, said sheets of record paper including clearance openings at the region of the fastening means, said fastening means including extensions overhanging and frictionally engaging the sheets of record paper whereby the 25 sheets of transfer paper may be withdrawn from between the sheets of record paper by withdrawing the fastening means from the clearance openings carrying the sheets of transfer paper with it. 30
